UNITED STATES PATENT OFFICE.

JOSEPH V. IRENIUS, OF NEWARK, NEW JERSEY, ASSIGNOR TO FERDINAND STRAUSS, INC., OF NEW YORK, N. Y., A CORPORATION OF NEW YORK.

MECHANICAL TOY.

Application filed December 18, 1919, Serial No. 345,636. Renewed June 8, 1922. Serial No. 566,898.

To all whom it may concern:

Be it known that I, JOSEPH V. IRENIUS, a citizen of the United States of America, residing at Newark, Essex County, State 5 of New Jersey, have invented certain new and useful Improvements in Mechanical Toys, of which the following is a full, clear, and exact description.

This invention relates to improvements 10 in toys, the object being to provide a self-propelled combination of a miniature vehicle, an animal-figure and a figure representing a clown, doll, or other figure, all arranged so that the animal and figure will 15 rock while the toy is in motion to give the appearance of a balky animal, the doll figure moving in unison with the movement of the animal figure.

To produce the result desired, I have arranged 20 a novel combination of parts, all of which will be hereinafter described and claimed, reference being had to the accompanying drawing, wherein:—

Fig. 1 is a side elevation of a toy embodying my improvement;

Fig. 2 is an enlarged fragmentary plan view, parts being omitted;

Fig. 3 is an enlarged cross-sectional view, the section being taken on a line 3—3 in 30 Fig. 1, the figure being omitted; and

Fig. 4 is a fragmentary diagrammatic side view.

As herein embodied, my invention comprises a body member 5, containing a motor mechanism of the usual variety employed to operate a driving disk 7 having teeth 8 through a portion of its periphery, one-half, for instance, as indicated in Fig. 3. The motor mechanism will not be described in detail any more than to state that it includes a spring 9, which is wound up or placed under tension by a key 10, said spring acting through a train of gears 11, 12, 13, and 14 to rotate the disk 7. The teeth of the disk mesh alternately with pinions 16 and 17 on an axle shaft 18 carrying wheels 19 and 20. During the rotation of the disk, the wheels will be rotated alternately in opposite directions, thereby causing the toy to alternately move backward and forward.

The device further includes a seat 21 pivotally connected to the body 5, said seat having secured thereto a figure 22 representing a clown, for instance. The seat is

out of balance, as can be seen, and will rest upon the peripheral edge of the disk 7. The pivotal points for the seat 21 consist of the turned out ends 23 of a pair of shafts 24 and 25, said ends passing through ears 60 26 of the body 5 and arms 27 of the seat 21. The shafts intermediate their ends engage the dash-board 28 of the body 5 and are preferably affixed to said dash-board, whereby they are rigidly held. The outer 65 ends of the shafts are pivotally connected to a figure 29 representing an animal, the point of connection being somewhat removed ahead of the center of gravity of said animal figure, whereby the said animal 70 figure will be out of balance and will tend to drop at the rear thereof, or remain depressed relative to the front end. The tendency of the rear end of the figure to drop will tend to maintain the seat in contact with disk 5, the animal figure and doll figure being connected by a wire, or the like, 30. It will be noticed that the pivotal points of the seat 21 are located ahead of the center of the figure 22. In other 75 words, the weight of the doll figure will be imposed upon the seat somewhat to the rear of the pivotal points of said seat; hence, as the animal figure and seat with its doll figure are out of balance and always 80 tending to drop, the seat will be maintained in contact with the periphery of disk 7.

It will be seen in Fig. 3 that the section of disk 7, carrying teeth 8, has a larger radius than the remainder of the disk; hence said section will raise seat 21, or swing it upwardly upon its pivots, during the rotation thereof. As soon as the section carrying the teeth clears the seat, the said 90 seat will drop or swing down. This swinging or up and down movement of the seat will cause the animal figure to swing upon its pivotal points and in combination with the back and forth movement of the toy 95 will give the appearance of a balky animal. As the pivotal points for the animal figure and seat are located ahead of the center of gravity of their respective parts, and as the doll figure is so positioned as to 100 cause its weight to be imposed upon said seat out of alignment with the pivotal points of said seat, and to the rear thereof, said animal figure, seat and doll will tend 105 to swing downwardly; hence disk 7 func- 110

tions only to raise the seat, and cause the back end of the animal figure to rise.

Having described my invention, what I claim and desire to secure by Letters Patent is:

1. A toy comprising a body member, a seat pivotally connected thereto, wheels carried by the body member, a motor mechanism, a disk operated by the motor mechanism, a portion of said disk being of greater radius than the remainder of the disk, teeth carried by that portion of the disk having the greater radius, a shaft for said wheels, gears carried by said shaft to mesh with the teeth on said disk, said seat being arranged to rest by gravity upon the periphery of said disk.
2. In a toy member, a motor mechanism carried thereby, wheels carried by the body member, a seat pivotally connected to said body, the pivotal points for said seat being out of alinement with the center of gravity of said seat whereby the free end of said seat will tend to drop, and means operable by the motor mechanism arranged to rotate said wheels and to cause said seat to swing upon its pivots.
3. In a toy, a body member, a motor mechanism carried thereby, wheels carried by the body member, a seat pivotally connected to said body, the pivotal points for said seat being out of alinement with the center of gravity of said seat whereby the free end of said seat will tend to drop, means operable by the motor mechanism arranged to rotate said wheels and to cause said seat to swing upon its pivots, and a doll figure carried by said seat.
4. In a toy, a body member, a motor mechanism carried thereby, wheels carried by the body member, a seat pivotally connected to said body, the pivotal points for said seat being out of alinement with the center of gravity of said seat whereby the free end of said seat will tend to drop, means operable by the motor mechanism arranged to rotate said wheels and to cause said seat to swing upon its pivots, an animal figure pivotally connected with said body and means connecting the animal figure and doll figure.
5. In a toy, a body member, a motor mechanism carried thereby, wheels carried by the body member, a seat pivotally con-

nected to said body, the pivotal points for said seat being out of alinement with the center of gravity of said seat whereby the free end of said seat will tend to drop, means operable by the motor mechanism arranged to rotate said wheels and to cause said seat to swing upon its pivots, a doll figure carried by said seat, shafts carried by the body member, an animal pivotally connected to said shafts, and means connecting the doll figure and the animal figure.

6. In a toy, a body member, a seat pivotally connected thereto, the pivotal points for said seat being out of alinement with the center of gravity of the seat, a doll figure carried by the seat positioned to cause the weight thereof to be imposed upon said seat between the pivotal points and the free end of said seat, shafts carried by the body having their ends turned out to engage said body and serve as pivots of the seat, an animal figure pivotally connected to said shafts at the opposite ends, means connecting the animal figure and doll figure, wheels carried by the body, a motor mechanism carried by the body, and means operable by the motor mechanism to rotate the wheels and cause said seat to swing upon its pivots.

7. In a toy, a body member, a seat pivotally connected thereto, the pivotal points for said seat being out of alinement with the center of gravity of the seat, a doll figure carried by the seat positioned to cause the weight thereof to be imposed upon said seat between the pivotal points and the free end of said seat, shafts carried by the body having their ends turned out to engage said body and serve as pivots of the seat, an animal figure pivotally connected to said shafts at the opposite ends, means connecting the animal figure and doll figure, a shaft carried by the body, wheels carried by the shaft, gears also carried by the shaft, a disk operable by the motor mechanism and teeth carried by the disk to engage said gears to rotate said wheels, said disk being arranged to swing said seat upon its pivots.

Signed at New York city, N. Y., this 11 day of December, 1919.

JOSEPH V. IRENIUS.
